(74) *Attorney, Agent, or Firm* — ArentFox Schiff LLP

(57) **CLAIM**

The ornamental design for packaging, as shown and described.

DESCRIPTION

FIG. 1 is a front right perspective view of a first embodiment of a packaging showing our new design;

FIG. 2 is a rear left perspective view of the design shown in FIG. 1;

FIG. 3 is a front view of the design shown in FIG. 1;

FIG. 4 is a top view of the design shown in FIG. 1;

FIG. 5 is an expanded view of the design shown in FIG. 1;

FIG. 6 is a front right perspective view of a second embodiment of a packaging showing our new design;

FIG. 7 is a rear left perspective view of the design shown in FIG. 6;

FIG. 8 is a front view of the design shown in FIG. 6;

FIG. 9 is a rear view of the design shown in FIG. 6;

FIG. 10 is a right side view of the design shown in FIG. 6;

FIG. 11 is an expanded view of the design shown in FIG. 6;

FIG. 12 is a front right perspective view of a third embodiment of a packaging showing our new design;

FIG. 13 is a rear left perspective view of the design shown in FIG. 12;

FIG. 14 is a front view of the design shown in FIG. 12;

FIG. 15 is a top view of the design shown in FIG. 12; and,

FIG. 16 is an expanded view of the design shown in FIG. 12. The broken lines in the Figures illustrate portions of the packaging that form no part of the claimed design.

1 Claim, 16 Drawing Sheets
